UNITED STATES PATENT OFFICE.

OLOF V. BLOM, OF FRESNO, CALIFORNIA.

DEVICE FOR TREATING SMELTER-FUMES.

1,098,611.

Specification of Letters Patent. Patented June 2, 1914.

Application filed April 7, 1913. Serial No. 759,274.

To all whom it may concern:

Be it known that I, OLOF V. BLOM, a citizen of the United States, residing at Fresno, in the county of Fresno, State of California, have invented certain new and useful Improvements in a Device for Treating Smelting-Fumes; and do declare the following to be a full, clear, and exact description of the same, such as will enable others skilled in the art to which it appertains to make and use the same, reference being had to the accompanying drawings, and to the characters of reference marked thereon, which form a part of this application.

This invention relates to improvements in a mechanism for treating the fumes of smelters used for roasting and smelting ores, the object of the invention being to produce a means whereby the deleterious material in such fumes may be precipitated prior to the fumes escaping to the atmosphere for the purpose of removing such deleterious elements in order that they may not spread and do damage to the property surrounding the smelter. As is a well known fact, the deleterious elements of these fumes are now extremely injurious to trees and vegetation and in fact all kinds of property surrounding the smelter and this has resulted in a great many of the smelters being enjoined from operation. The object of my invention is to overcome all of these difficulties.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claim.

The figure of the drawings is a side elevation, partly in section, of a portion of my improved mechanism.

Referring now more particularly to the characters of reference on the drawings, the numeral 1 designates the furnace provided with suitable burners and outlets of any desired type and hence no specific description of the same is here entered into. In addition to this, I provide a system of auxiliary oil and compressed air inlets 2 adapted to assist in the consumption of the products delivered to said furnace 1.

In applying my improved structure, I preferably dispose the same on a hillside

or in an inclined manner and the same consists of a flue or outlet 3 arranged in steps, each step being provided at its junction with an adjacent step with an inclined receiving and delivering box 4 having a door 5 adapted to deliver into a trough 6. At each junction of each adjacent pair of said steps I provide a spray nozzle 7 connected by pipes 8 with water tanks 9. Then as the fumes from the furnace 1 pass through the various steps they are subjected to a water or other solution spray and such of the elements thereof as are susceptible of precipitation are precipitated and then these precipitated elements will drop into the receiving and delivering box 4 from whence they may pass into trough 6. The overflow water from the members 4 may be drained through pipes 5 into the next lower water tank 9.

The arrangement of the structure into steps is so as to place the chutes 4 under their adjacent upper steps so that the elements precipitated by the water spray at that point will readily fall into the chutes. Instead of the water spray used compressed air may be admitted through a pipe 10 or other similar elements may be admitted to the spray member 7, which elements are found adaptable for precipitating certain of the elements in the fumes.

All of the operations of the device will of course depend upon the character of the fumes being treated and the necessary solutions and other elements necessary to their precipitation, the especial point of the invention being the stepped structure and in admitting the precipitating element at the junction of each step, with the receiving chute below each step to receive the precipitated elements.

To prevent any of the fumes escaping when the furnace is being charged, I provide a series of control gates, which structure is as follows, namely: The numeral 11 indicates a receiving gate opening into a chamber 12 which has a gate 13 opening into another chamber 14 communicating at 15 with the flue structure 3. This chamber 14 has a gate 16 communicating with the furnace 1. The charge of ore 17 is first admitted through the gate 11 into the chamber 12. The gate 11 is then closed and the gate 13 opened. The gate 13 is then closed and the gate 16 opened which admits the charge of the furnace 1, any fumes escaping therefrom passing through the chamber 14 and

opening 15 into the flue structure 3. The initial chamber 12 is always closed when the chamber 14 is opened and thus this prevents any escape of the fumes to the atmosphere when the furnace is being charged.

From the foregoing description it will be readily seen that I have produced such a device as substantially fulfills the objects of the invention as set forth herein.

10 While this specification sets forth in detail the present and preferred construction of the device, still in practice such deviations from such detail may be resorted to as do not form a departure from the spirit of the 15 invention.

Having thus described my invention what I claim as new and useful and desire to secure by Letters Patent is:—

A conduit for use in treating smelter

fumes, the same comprising an inclined conduit arranged in steps, a receptacle opening into said conduit just below the juncture of adjacent steps and disposed at substantially right angles to said conduit whereby the bottom of each receptacle inclines toward its lower corner, a door in the lower corner of each receptacle, another receptacle disposed below each of said first named receptacles, and a pipe leading from the upper side of one end of each of said first named receptacles to the corresponding receptacle below the same, as described.

In testimony whereof I affix my signature in presence of two witnesses.

OLOF V. BLOM.
